US00D957729S

(12) **United States Design Patent** (10) **Patent No.:** **US D957,729 S**
Yan (45) **Date of Patent:** ** *Jul. 12, 2022

(54) **VAPORIZING DEVICE**(71) Applicant: **NJOY, LLC**, Scottsdale, AZ (US)(72) Inventor: **Simon Yan**, New York, NY (US)(73) Assignee: **NJOY, LLC**, Scottsdale, AZ (US)

(*) Notice: This patent is subject to a terminal disclaimer.

(**) Term: **15 Years**(21) Appl. No.: **29/778,231**(22) Filed: **Apr. 12, 2021****Related U.S. Application Data**

(63) Continuation of application No. 29/694,801, filed on Jun. 13, 2019, now Pat. No. Des. 918,466.

(51) **LOC (13) Cl.** ..... **27-02**(52) **U.S. Cl.**USPC ..... **D27/162**(58) **Field of Classification Search**

USPC D27/162, 100, 101, 163–165, 172, D27/174–176, 183, 185–194; D24/110,

D24/110.5; D23/366

CPC A24F 47/002; A24F 47/006; A24F 47/008; A61M 15/00; A61M 15/06

See application file for complete search history.

Primary Examiner — Rebecca Tsehay(74) *Attorney, Agent, or Firm* — Bookoff McAndrews, PLLC(57) **CLAIM**

The ornamental design for a vaporizing device, as shown as described.

DESCRIPTION

FIG. 1 is a perspective view of the vaporizing device; FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the vaporizing device that form no part of the claimed design.
